(57) **CLAIM**

The ornamental design for a case for electronic communications device, as shown and described.

DESCRIPTION

FIG. 1 is a front, right-side, and top perspective view of a case for electronic communications device showing my new design;

FIG. 2 is a rear, left-side, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear, left-side, and top perspective view thereof in the folded position; and,

FIG. 10 is an enlarged detail view of the encircled region in FIG. 9 to demonstrate the pattern placed on the surface of the case.

The dot-dash broken lines in FIGS. 9 and 10 form no part of the claimed design and delineate a portion of the claimed design that is shown on an enlarged scale in FIG. 10. The dashed broken lines throughout the drawing figures depict portions of the case for electronic communications device that form no part of the claimed design. The dashed broken lines and regions bounded by dashed broken lines form no part of the claimed design.
